PLASTIC FLOOR

John J. Widmayer, Washington, D. C.

Application October 16, 1941, Serial No. 415,313

5 Claims. (CL. 72—66)

This invention consists of an improvement in plastic floors wherein I provide a novel form of fibrous block used in conjunction with interfitting soffit members, also preferably made of fiber to prevent the formation of a plastic film or coat on the ceiling.

It is within the contemplation of this invention to construct a plastic floor including fiber blocks in accordance with the teaching of my invention Patent No. 2,260,425, the blocks of this invention however being of different construction and adapted to complement soffit pieces whereby seepage of the plastic material between the blocks is eliminated.

A further object of the invention is to provide a plastic floor comprised of a concrete mass and fibrous blocks, the blocks being parallelly arranged with concrete receiving channels therebetween, each of the blocks having marginal recesses in its lower face engaged by soffit pieces which span the distance between the channels and also the distance between the ends of the blocks and the floor beams, to prevent passage of the concrete or of any of the components or residuals thereof between the blocks into the zone or area of the ceiling.

Other objects will be apparent from the following description of the invention, taken in connection with the accompanying drawing, wherein

Fig. 1 is a plan view of a floor constructed in accordance with the present invention, a portion thereof being broken away to disclose details;

Fig. 2 is a cross sectional view taken on the line 2—2 of Fig. 1, looking in the direction of the arrows, showing to advantage the manner of assembling the concrete blocks and soffit pieces;

Fig. 3 is a fragmentary sectional view taken on the line 3—3 of Fig. 1, showing to advantage the manner in which the blocks and soffit members are engaged with a floor beam, and

Fig. 4 is a perspective view of a block constructed in accordance with the present invention.

In order to illustrate the application of my invention, I have in Fig. 1 illustrated a part of a plastic floor 5 which may be composed of concrete and construction elements, made in accordance with the teaching of this invention, hereinafter more fully described. The floor also includes beams 6 of standard construction, adapted to support the floor in a well-known manner.

The floor of this invention includes parallelly arranged fibrous blocks 7, the lower face of each of which is provided with a marginal groove, the

sides 8 of which groove are co-extensive with the longitudinal axis of the blocks, the ends 9 of the groove being co-extensive with the transverse axis of the blocks.

5 The side grooves 8 are adapted to be engaged by soffit members 10 consisting preferably of fibrous slabs, these slabs being of a thickness corresponding to the depth of the groove so that the lower faces of the slabs will be uniplanar with the lower face of the blocks 7. The end grooves 9 are adapted to be engaged by soffit pieces or members 11 which are of identical construction to the soffit pieces 10 and are adapted for engagement in the end grooves 9 in the same manner in which the soffit pieces 10 are engaged in the side grooves 8. The ends of the soffit slabs 10 engage the adjacent marginal edges of the soffit slabs 11, as shown to advantage in Figs. 1 and 3.

10 The lower faces of the soffit members 11 are also in the same plane with the bottom faces of the soffit members 10 and with the bottom faces of the blocks 7. As is apparent, especially from Figs. 2 and 3, this arrangement provides not only a sealed ceiling which prevents the passage of any of the plastics therethrough, but likewise provides an uninterrupted ceiling capable of use with the plaster or other coating composition. Obviously the blocks and soffit members provide 15 an excellent plaster base, not only because of the interstices of the blocks and soffit members, but likewise because of the uniformity and evenness of construction of the bottom face of the floor.

20 Although I have described herein a preferred form of the invention wherein fiber blocks and fiber soffit slabs are used, interconnected in a special manner with the floor beams, I am aware that the invention is susceptible of use in other forms and susceptible of other uses, but it is of 25 importance herein that the blocks and soffit members be engaged to provide overlap joints for the purpose already described and hereinafter claimed.

What I claim is:

30 1. A plastic floor comprising fibrous blocks, spaced to provide plastic receiving channels therebetween, the lower side and end edges of each block being undercut to provide grooves, and fibrous inflexible slabs mounted in said grooves to provide a moisture-proof joint between the lower faces of adjacent blocks at the bottom of each channel.

35 2. A plastic floor comprising parallelly arranged fibrous blocks spaced to provide plastic receiving spaces, therebetween, the bottom faces

of the blocks being undercut to provide marginal grooves, and fibrous soffit pieces engageable in said grooves to prevent plastic seepage between and below the blocks.

3. Floors for buildings including fiber blocks aligned in rows, the latter being spaced to provide plastic receiving channels, sealing means in the bottom of each channel comprising a soffit member arranged between the lower adjacent faces of the blocks, said lower adjacent faces being grooved to interfit the soffit members and prevent passage of the plastic materials through the bottom face of the floor.

4. A concrete floor including parallelly arranged beams, parallelly arranged fibrous blocks positioned between said beams and spaced to provide concrete receiving channels between the sides

of the blocks and between the ends of the blocks and said beams, and soffit members engaged with said beams and interfitting the lower margins of the blocks to provide overlapped joints between the blocks and soffit members.

5. A plastic floor comprising parallelly arranged fibrous blocks spaced to provide plastic receiving spaces therebetween, the bottom faces of the blocks being undercut at their margins to 10 provide a groove in each of the lower edges of the block with an overhanging abrupt shoulder, and fibrous inflexible soffit pieces engaged in said grooves and abutting the shoulders thereof to 15 form a liquid seal between the blocks and soffit pieces.

JOHN J. WIDMAYER.
